UNITED STATES PATENT OFFICE.

CHARLES H. HASBROUCK, OF BINGHAMTON, NEW YORK.

MACHINE FOR PROTECTING CHECKS AND THE LIKE.

1,302,655.

Specification of Letters Patent.

Patented May 6, 1919.

Application filed March 3, 1917. Serial No. 152,425.

To all whom it may concern:

Be it known that I, CHARLES H. HASBROUCK, a citizen of the United States, and resident of Binghamton, county of Broome, 5 and State of New York, have invented certain new and useful Improvements in Machines for Protecting Checks and the like, of which the following is a specification.

This invention relates to machines for 10 protecting checks and the like.

The primary object of this machine is to provide a device of the above mentioned character which will print checks, drafts or other documents in such a manner as to 15 effectively prevent any alteration of the same.

A further object of this invention is to provide a machine for printing and protecting checks and the like which is comparatively simple in construction, easy and inexpensive to manufacture, strong and durable.

Another object of this invention is to provide a machine for printing checks which will more effectively prevent the alteration 25 of same and give increased protection to the maker of a check than in check writers of ordinary construction.

The above and other objects and advantages will appear from the following description taken in conjunction with the accompanying drawings and the particular features of novelty will be pointed out in the appended claims.

Common subject matter which is shown 35 and described in this application but not claimed herein is claimed in my copending applications for machines for protecting checks and the like, one application being filed August 1, 1916, Serial No. 112,539, and 40 the other being filed November 27, 1917, Serial No. 204,210.

In the drawings in which similar characters of reference denote similar parts in the several views,

45 Fig. 1 is a side elevation of the device, with a cover therefor shown in section;

Fig. 2 is a top view of the device, also with the cover in section;

50 Fig. 3 is a side view of the machine, certain parts being shown in section;

Fig. 4 is a view taken on the line 4—4 of Fig. 3;

Fig. 5 is an end elevation of the machine;

55 Fig. 6 is a sectional view taken on the line 5—5 of Fig. 1;

Fig. 7 is an enlarged view of a printing wheel;

Fig. 8 is a face view of the same; Fig. 9 is a face view of a scale bar; Fig. 10 is a perspective view of a frame; 60 Fig. 11 is a central vertical longitudinal section view of the same;

Fig. 12 is a perspective view of a portion of a rack bar;

Fig. 13 is a transverse sectional view of 65 the same showing a portion of an upstanding arm associated therewith, and,

Fig. 14 is a side elevation of a spring pressed locking arm.

Referring to the drawings, the numeral 70 1 denotes the base of the machine, upon which is mounted a raised plate 2 beneath which the checks, drafts or other documents are to be inserted. Mounted on the base 1 and near one end thereof is a member 3 75 which supports shafts 4 and 5. The shafts, as shown, are arranged substantially parallel to each other. Mounted near the opposite end of the base 1 and arranged substantially parallel to shafts 4 and 5 is a supporting member 6, the head of which is provided with parallel arranged slots 7 and 8. A projection 10 at the end of frame 9 is slidably engaged in slot 8. Secured to the supporting member 6 and extending across 80 slots 7 and 8 is a spring 11, the purpose of which will be hereinafter described. Mounted on the shaft 5 and positioned between the opposite sides of the frame 9 is 85 a contractile coil spring 12.

The numeral 13 denotes a relatively small plate which is secured to plate 2 and to which is pivoted near one end thereof a bell crank lever 14. One arm of lever 14 is provided with a slot 15 which engages a pin 16 secured to the frame 9. The other arm of the lever 14 is provided with a slot 17' which engages the pin 17 secured to an operating lever 19 which in turn is pivotally secured to the plate 13 as shown at 18.

Extending through the frame 9 and rigidly secured thereto is a shaft 20 to which is splined a printing wheel 21 and a pinion 22. The printing wheel 21 is provided with a plurality of slots 23, each of which terminates in an enlarged opening 24. Mounted on the face of the printing wheel 21 are suitable background blocks 26 provided with indicia 25 as shown. This background block 26 may be provided with either serrated or smooth faces as shown.

Preferably formed integral with the frame 9 at a point adjacent shaft 20 is a substantially right-angle member 27, one arm of

which extends over the printing wheel 21, as shown clearly in Fig. 6, and supports an inverted substantially U-shaped spring member 28 provided with bearings 29 at its 5 extremities. Mounted in bearings 29 are inking rollers 30 adapted to contact with the printing wheel 21. Mounted on the base 1 by means of projections 31 and 32 and positioned parallel to the frame 9 is a 10 bar 33 which is provided throughout almost its entire length with a slot 34. Positioned on the plate 2 and arranged parallel to the bar 33 and near same is a guide-way 35, as shown in Fig. 2. Slidably mounted 15 within this guide-way 35 is a rack bar 36 which is adapted to mesh with the pinion 22 and impart a rotary movement to the printing wheel 21 upon a sliding movement of the rack bar. The rack bar 36 is provided with joints 37 and 38, one of which is clearly shown in Fig. 12.

Secured to the rack bar 36, as clearly shown in Figs. 5 and 13, is an upstanding arm 39 which is provided with projections 40. The projections 40 are adapted to slidably fit within the slot 34 and bar 33. An operating handle 41' is secured to the upstanding arm 39. The upper end of arm 39 forms a pointer 41, as shown in Fig. 5. Secured to the plate 2, as clearly shown in Figs 5 and 14, are projections 42, to each of which is pivoted a spring-pressed locking arm 43, one end of which is adapted to engage the teeth of rack bar 36 and lock same 35 against longitudinal movement. Mounted on each end of the frame 9 and preferably formed integral therewith is a downwardly projecting arm 45 which is adapted to contact with one end of arm 43 and disengage 40 the other end from the teeth of rack bar 36. In practice, two of these locking arms are used, one positioned on each side of the type wheel 21. Mounted on the plate 2, as clearly shown in Figs. 5 and 6, is a projection 46 which carries a pin 47 which faces the printing wheel 21. The base 1 opposite the printing wheel 21 is provided with an opening 48 which registers with a similar opening 49 in plate 2. Positioned on the 50 under side of the base 1 and adjacent the opening 48 is a substantially U-shaped frame 50 which has mounted therein, as clearly shown in Figs. 3 and 10, an adjustable spring-pressed secondary frame 51. This frame 51 has mounted therein a revolvable platen wheel 52 over which the back ground blocks 26 carried by the printing wheel 21 are adapted to be moved. A screw 53 is secured to the secondary frame 51 and 60 passed through the U-shaped frame 50, said screw being free to reciprocate within the opening through which it is passed. As shown in Fig. 11, the frame 50 is provided with openings 54 and 55 which receive plungers 56 and 57 which carry springs 58

and 59 respectively. It is obvious that the vertical movement of frame 51 is limited and can be adjusted by means of nut 60 mounted on the screw 53.

Adjustably mounted on the base 1 are 70 guide members 61. It can be readily seen that by adjusting the guide members 61, checks, drafts or other documents may be inserted in the machine and properly guided.

75 A cover 62 is provided for this machine which is preferably of substantially rectangular form. A slot 63 is provided in one of the sides thereof to allow the operation of the handle 19. To permit the longitudinal 80 movement of the handle 41' a slot 64 is provided in the cover 62. Arranged substantially parallel to the guide-way 35 and rack bar 36 and positioned in the cover 62 is a slot 65, which slot permits the longitudinal 85 movement of the arm 39 and its pointer 41. The pointer 41 is adapted for movement along a scale bar 66 which is clearly shown in Fig. 9. As shown in this figure, this scale bar permits the printing of the 90 exact amount of the check, draft or other document, the numerals being from "1 to 20" and from "20 to 90" (progressing by 10's). The words "dollars", "hundred" and "thousand" and three cross marks also appear.

95 The interior of the cover is provided with raised track portions 66' and 67 which are so positioned that upon sufficient longitudinal movement of the rack bar 36, one end 100 of the bar will be carried in one of the tracks 66' or 67 according to the direction of movement of the bar 36. This is made possible, it is obvious, by joints 37 and 38.

105 From the above description, it is obvious that the operation of the device is as follows: When it is desired to print a certain amount on a check, draft or other document, the check or the like is inserted in the space between the base 1 and the plate 2. The 110 printing wheel is then rotated to the desired position by means of the handle 41' which moves the rack bar 36 laterally and rotates pinion 22. The desired position is found by the pointer 41 registering with scale bar 66. 115 The lever 19 is then moved downwardly by its handle, which will cause the frame 9 carrying the printing wheel 21 to move forwardly carrying with it the inserted check. The pin 47 will be inserted in one of the enlarged openings 24 of the printing wheel and hence eliminate any rotary movement of same. As the check or other document goes over spring-pressed platen wheel 52, the indicia on the printing wheel will be impressed upon the check or other document. When the frame 9 is moved, as above described, it is obvious that the spring 12 is compressed and the projection 10 on frame 9 will travel in slot 8 of projection 6. It 130

can also be seen from Fig. 4, that as the projection 10 reaches the end of slot 8, the spring 11 will force the projection 10 into slot 7, thereby raising the frame 9. The printing wheel will consequently be raised from contact with the check or other document. The spring 12 will serve to return the frame 9 to its normal position and hence position projection 10 again in slot 8 ready for another operation similar to that described above. It can be readily seen by Fig. 5 that as the frame 9 moves forwardly, the arm 45 will allow the locking member 43 to engage the teeth of rack bar 36 and prevent same from displacement. For convenience, as before mentioned, two of these locking means are provided.

In reduction to practice, I have found that the form of my invention illustrated in the drawings and referred to in the above description as the preferred embodiment is the most efficient and practical, yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention as defined in the appended claims.

What I claim and desire to secure by Letters Patent of the United States, is:

1. A check writer comprising a base, a frame adapted for transverse movement with respect to said base, a printing wheel carried by said frame, a pinion carried by said printing wheel, a movable rack adapted to engage said pinion, a spring for normally maintaining engagement between the pinion and rack, means for moving said pinion transversely out of engagement with said rack, and means for locking said rack when said pinion is moved out of engagement with the same.

2. A check writer comprising a base, a frame adapted for transverse movement with respect to said base, a printing wheel carried by said frame, a pinion carried by said printing wheel, a movable rack adapted to engage said pinion, a spring for normally maintaining engagement between said pinion and rack, a lever adapted to move said frame transversely with respect to said base and disengage said rack and pinion, and means for locking said printing wheel against rotary motion when said rack and pinion are disengaged.

3. A check writer comprising a base, a frame adapted for transverse movement with respect to said base, a printing wheel

carried by said frame, a pinion carried by said printing wheel, a movable rack adapted to engage said pinion, a spring for normally maintaining engagement between said pinion and rack, a lever adapted to move said frame transversely with respect to said base and disengage said rack and pinion, a pin for locking said printing wheel against rotary motion when said rack and pinion are disengaged, and means for locking said rack when said rack and pinion are disengaged.

4. A check writer comprising a base, a frame adapted for transverse movement with respect to said base, a printing wheel carried by said frame, a pinion carried by said printing wheel, a plurality of inking rollers carried by said frame and adapted to contact the face of said printing wheel, a movable rack adapted to engage said pinion, a spring for normally maintaining engagement between said pinion and rack, a lever adapted to move said frame transversely with respect to said base and disengage said rack and pinion, a pin for locking said printing wheel against rotary motion when said rack and pinion are disengaged, and means for locking said rack when said rack and pinion are disengaged.

5. A check writer comprising a base, a frame adapted for transverse movement with respect to said base, a printing wheel carried by said frame, a pinion carried by said printing wheel, a movable rack adapted to engage said pinion, a spring for normally maintaining engagement between said pinion and rack, a lever adapted to move said frame transversely with respect to said base and disengage said rack and pinion, a platen wheel carried by said base, said platen wheel being adapted to engage the face of said printing wheel, and means for locking said printing wheel against rotary motion when said rack and pinion are disengaged.

6. A device of the character described comprising a base, a movable frame mounted thereon, a printing wheel journaled within said frame, a pinion carried by said printing wheel, a rack adapted to engage the said pinion to rotate said printing wheel, a lever for moving said pinion out of normal engagement with said rack, means for locking said printing wheel against rotary movement when said pinion is moved out of engagement with said rack, means for locking said rack when said pinion is moved out of engagement therewith, and a spring adapted to move said pinion into engaging position.

CHAS. H. HASBROUCK.
